UNITED STATES PATENT OFFICE

124,622

DESIGN FOR A BOX

Ronald L. Hilton, Chicago, Ill., assignor of one-half to Boynton & Company, Chicago, Ill., a corporation of Illinois

Application December 9, 1939, Serial No. 88,786

Term of patent 3½ years

To all whom it may concern:

Be it known that I, Ronald L. Hilton, a citizen of the Dominion of Canada and a resident of Chicago, in the county of Cook and State of Illinois, have invented a new, original, and ornamental Design for a Box, of which the following is a specification, reference being had to the accompanying drawing, forming a part thereof, and in which:

Fig. 1 is a perspective view of a box showing my new design, the opposite side wall being identical to the side wall shown in Fig. 1;

Fig. 2 is an end elevational view of the same

on an enlarged scale, and as seen from line 2—2 in Fig. 1;

Fig. 3 is a perspective view of the box shown in Fig 1, on a slightly reduced scale with respect thereto, with one lid portion thereof in partly opened condition, showing my new design; and

Fig. 4 is a longitudinal section on a slightly larger scale with respect to the box illustrated in Fig. 1, showing my new design.

I claim:

The ornamental design for a box, as shown.

RONALD L. HILTON.
